UNITED STATES PATENT OFFICE.

JOHN H. KERSTETER, OF STATE COLLEGE, PENNSYLVANIA.

STAPLE-SETTING IMPLEMENT.

1,205,547.

Specification of Letters Patent. Patented Nov. 21, 1916.

Application filed April 21, 1916. Serial No. 92,744.

To all whom it may concern:

Be it known that I, JOHN H. KERSTETER, a citizen of the United States, residing at State College, in the county of Center, State of Pennsylvania, have invented certain new and useful Improvements in Staple-Setting Implements; and I do hereby declare the following to be a full, clear, and exact description of the invention, such as will enable others skilled in the art to which it appertains to make and use the same.

The present invention is directed to improvements in devices for driving staples, and has for its object to provide a device of this character so constructed that a number of staples can be held in position to be successively driven.

A further object of the invention is to provide a device of this character which is exceedingly simple in construction, and one in which means are provided for holding a plurality of staples which are fed one at a time to a position to be driven by the driving rod.

With these and other objects in view, this invention resides in the novel features of construction, formation, combination and arrangement of parts to be hereinafter more fully described, claimed and illustrated in the accompanying drawing, in which:—

Figure 1 is a side elevation of the device. Fig. 2 is a front view. Fig. 3 is a sectional view on line 3—3 of Fig. 1. Fig. 4 is a similar view on line 4—4 of Fig. 1. Fig. 5 is a longitudinal sectional view. Fig. 6 is an end view.

Referring to the drawing, 1 indicates the handle, said handle having a longitudinal bore 3 formed therein, and in which is slidably mounted a spring pressed drive rod 4, the lower end of which being provided with a curved recess 5 for engaging the bight of a staple. The lower end of the handle 1 is provided with a cut away portion 6, the purpose of which will appear later.

Removably engaged with the lower end of the handle 1 is a plate 7, said plate having its lower end formed with a horizontal flange 8 which supports the outer edge of the staple supporting bar 9. The inner edge of the bar 9 is spaced from the adjacent walls of the handle 1 so as to permit the passage of the staples as they slide from the bar, whereby the staples will be successively positioned under the drive rod 4.

Hingedly associated with the handle 1 is a spring pressed guard 10, which is substantially semi-circular in cross section so as to receive the upper edge of the bar 9, said guard serving to hold the staples against accidental disengagement from the bar 9. The outer end of the guard 10 is provided with a yoke 11, the legs of which straddle the bar 9 so as to prevent the staple sliding off the outer end of the bar.

The handle 1 has associated with its lower end a claw bar 12 which is for the purpose of pulling nails or staples.

The handle 1, bar 9 and guard 10 are preferably formed from aluminum, while the drive rod is formed from steel.

In use, a plurality of staples are engaged with the bar 9, and the guard 10 under the action of its spring 13 will prevent the disengagement of the staples from the bar. The handle 1 is held in a horizontal position at one end so that the bar 9 will be directed upwardly thus causing the staples to gravitate successively into the path of movement of the drive rod 4 which being struck a sharp blow will drive the staple into the post.

The device is particularly adapted for use in stapling fence wires to the supporting posts, but it will be of course understood that it can be used in any other connection seen fit.

What is claimed is:—

A device of the class described comprising a handle having a longitudinal bore formed therein, a spring retractable drive rod slideable in the bore, a staple supporting bar having its inner end disposed adjacent the inner end of said bore and so arranged that the staples will be successively fed into the path of movement of the drive rod, a spring pressed guard carried by the handle for inclosing one edge of the staple supporting bar, and a yoke carried by the outer end of the guard and arranged to straddle the supporting bar to retain the staples thereon, as and for the purpose set forth.

In testimony whereof, I affix my signature, in the presence of two witnesses.

JOHN H. KERSTETER.

Witnesses:

MICHAEL WOMER,
REUBEN FRIDY.
